UNITED STATES PATENT OFFICE.

EDMUND M. PITTS, OF PHILADELPHIA, PENNSYLVANIA.

DISPLAY DEVICE.

Application filed September 21, 1921. Serial No. 502,277.

To all whom it may concern:

Be it known that EDMUND M. PITTS, citizen of the United States, residing at Philadelphia, in the county of Philadelphia and

5 State of Pennsylvania, has invented certain new and useful Improvements in Display Devices, of which the following is a specification, reference being had therein to the accompanying drawings.

10 The invention relates to display devices, and has for its object to provide a device of this character which is preferably formed from paper or other fibrous material, and so constructed that an article to be displayed 15 may be attached thereto and held against a support, such for instance as a window glass by members provided with adhesive material thereon.

A further object is to provide a display 20 device comprising a body portion having means for receiving and holding a carton, said body portion being provided with integral members the marginal edges of which are provided with adhesive material, said 25 integral members being adapted to be bent in the direction of a support and be adhesively attached thereto, in such a manner as to hold the carton in engagement with the support. Also to provide a carton holding 30 device which may be attached to a window for displaying the carton, said device also forming a sign on which various advertising matter may be printed.

With the above and other objects in view 35 the invention resides in the combination and arrangement of parts as hereinafter set forth, shown in the drawings, described and claimed, it being understood that changes in the precise embodiment of the invention 40 may be made within the scope of what is claimed without departing from the spirit of the invention.

In the drawings:—

Figure 1 is a plan view of one of the 45 blanks for forming the display device, showing the inner side of the device.

Figure 2 is a front elevation of the device after the same has been folded and ready to apply to a supporting glass.

50 Figure 3 is a vertical sectional view taken on line 3—3 of Figure 2, showing the device attached to a supporting glass.

Figure 4 is a horizontal sectional view taken on line 4—4 of Figure 1, showing the 55 device applied to a supporting glass.

Figure 5 is a plan view of a modified form of display device, wherein a carton or box is held between bent out integral lugs.

Figure 6 is a horizontal sectional view 60 through the form of device shown in Figure 5, showing the same attached to a window frame and holding the carton in engagement with the pane.

Figure 7 is a detail perspective view of 65 the carton holding portion of the device shown in Figures 5, and 6.

Figure 8 is perspective view of another form of holding device wherein the rear vertical corners of the carton or box extend 70 through vertically disposed openings in the body of the holding device.

Figure 9 is a horizontal sectional view 75 through the box holding portion of the device shown in Figure 8, showing a carton or box being held therein in engagement with a window frame.

Referring to the drawings, and particularly to Figures 1 to 4 inclusive, the numeral 1 designates the body portion of a 80 sheet of material, which sheet of material may be formed from cardboard, paper or from any other material, however preferably from heavy paper or cardboard. The body portion 1 is substantially rectangular 85 shaped, and may be provided with vertically disposed indentations or scorings 2 and horizontally disposed indentations or scorings 3, which indentations or scorings form a rectangular shaped body as clearly 90 shown in Figures 1 and 2. The corners of the body portion 1 are provided with V-shaped incisions 4, which form triangular shaped lugs 5, adapted to be bent inwardly on scored lines 6 for engagement under the 95 top 7 and the bottom 7 of a carton 9 in which goods are disposed, and which cartons are desired to be displayed, on a window, show case or a door, where it can be easily and readily observed by an approaching customer.

It will be seen that the carton 9 may be held as shown in Figure 2, or at a reverse inclination if so desired. Extending outwardly from the sides of the body portion 1 are integral angularly shaped 105 members 10, which members may be provided with a line 11 on which a bend may be obtained which will be straight after the members 10 have been bent inwardly on the lines 2. After the members 10 have 110

been bent to a vertical plane on the lines 11, the integral members 12 which extend outwardly from the upper and lower ends of the rectangular shaped body member 1 are bent 5 in the same direction as the integral members 10 until their angularly disposed edges 12^a engage the angularly disposed edges 10^a of the members 10, thereby forming a dished support as clearly shown in Figures 3 and 10 4. After the members 12 have been bent as set forth, they are again bent on the lines 13 until their gummed portions 14 are in the same plane as the gummed portions 15 of the members 10, at which time, after the 15 gummed portions 14 and 15 have been moistened, the device as a whole may be adhesively attached to a glass 16 of a window door or show case in such a manner that the carton 9 will be held in engagement 20 with the glass 16 so that it may be observed by a customer or attract the attention of a prospective customer.

By forming the device from paper or other sheet material, it is obvious that it 25 may be easily and compactly packed for shipment and storage and set up as desired.

Referring to Figures 5 to 7 inclusive, it 30 will be seen that a strip of material 17 is provided, which strip is provided with adhesive material 18 at its ends and with a plurality of tongues 19, which tongues may be bent outwardly as shown in Figure 7 in such a manner as to engage the sides of a carton 20 for holding the carton in engagement 35 with one surface of the glass 21, after the adhesive 18 has been moistened and the device bent to the forms shown in Figure 6 and adhesively joined to the glass. The tongues 19 are formed integral with the sheet 17, and it is obvious that the tongues 40 when in the same plane as the sheet 17, will allow the sheets to be compactly packed for shipment.

Referring to Figures 8 and 9, the device in 45 this form comprises an elongated strip 22, which strip is adapted to have printed thereon advertising matter and is provided with adhesive material 23 at spaced points. The strip 22 is bent at 24 at an obtuse angle 50 to the portion 22 and at 25 so as to form a box receiving portion 26 in the same plane as the strip 22. After the box receiving portion 26 has been formed the strip is bent at 27 to form an angularly disposed 55 portion 28 extending towards the pane of glass 29 and is bent at 30 to form the adhesive carrying portions 31 in the same plane as the strip 22. The strip 22 is provided with oppositely disposed and opposed 60 U-shaped slots 32, which have their arms terminating adjacent the bending points 25 and 27, thereby providing means whereby when the bends 25 and 27 are formed, vertically disposed recesses 33 are provided. 65 which recesses receive the rear vertical cor-

ners 34 of a carton or box 35, which is held against displacement and in engagement with the plane 29.

From the above it will be seen that a carton or box displaying device is provided, 70 which device is preferably formed from bendable material, and which may be easily and quickly bent to form for positively and rigidly holding a carton preferably in engagement with a transparent support, such 75 for instance as a window glass, a door glass, or a showcase glass.

The invention having been set forth what is claimed as new and useful is:—

1. A display device formed from a sheet 80 of material, means carried by said sheet of material whereby an article may be attached thereto, said sheet of material being adapted to be affixed to a supporting element to cover different areas thereof and to support articles of different size between the sheet of material and the supporting element.

2. A display device formed from a sheet of material, lugs carried by and formed integrally with the sheet of material and adapted to engage an article for holding the same on the sheet of material, said sheet of material being adapted to be affixed to a supporting element to cover different areas 95 thereof and to support articles of different size between the sheet of material and the supporting element.

3. A display device comprising a sheet of material, means whereby an article to be displayed may be attached thereto, an adhesive material carried by said sheet and forming means whereby the sheet at spaced points may be attached to a support, said sheet of material being adapted to be affixed to the 100 support to cover different areas thereof and to support articles of different size between the sheet of material and the support.

4. A display device formed from a sheet 110 of material, said device comprising a rectangular shaped body portion formed by scored lines, means whereby an article may be attached to said body portion, outwardly extending members carried by the sides and ends of the rectangular shaped body 115 portion and having their edges diverging but spaced from the adjacent edges of the adjacent portion, thereby allowing the outwardly extending portions when bent on their scored lines to come together for forming a dished member and adhesive material carried by said outwardly extending portions adjacent their outer edges and forming means whereby the display device may be attached to a support.

5. A blank for forming an article display device, said blank comprising a rectangular shaped sheet of material, a rectangular shaped central portion formed by scored lines, means disposed in said rectangular 120

shaped portion whereby an article to be disposed may be attached thereto, outwardly extending portions carried by the sides of the rectangular shaped portion and formed 5 by V-shaped notches extending inwardly from the corners of the sheet of material and having their converged ends terminating adjacent the corners of the rectangular shaped portion and adhesive material carried by said outwardly extending portions 10 adjacent their edges and forming means whereby the device may be adhesively attached to a support.

6. A display device for articles, said device being formed from a sheet of material 15 and dished, means for attaching an article within the dished portion thereof means for attaching the device to a window pane, and means whereby the sheet of material may be extended to all of its sides to cover different areas of the window pane, whereby articles of different size may be held between the sheet and window pane.

In testimony whereof I hereunto affix my signature.

EDMUND M. PITTS.
